UNITED STATES PATENT OFFICE.

GEORGE W. SWIFT, JR., OF BORDENTOWN, NEW JERSEY.

WINDOW-ENVELOP MACHINE.

1,275,788.

Specification of Letters Patent. Patented Aug. 13, 1918.

Application filed July 17, 1917. Serial No. 180,961.

To all whom it may concern:

Be it known that I, GEORGE W. SWIFT, Jr., of Bordentown, in the county of Burlington and State of New Jersey, have invented certain new and useful Improvements in Window-Envelop Machines, whereof the following is a specification, reference being had to the accompanying drawings.

My invention relates to a window envelop

10 machine in which the envelop patch is initially applied to the envelop web at a point other than the region of the window opening. It is thus possible to defer the cutting of the window openings from the envelop web until after the window patches have been brought into accurately spaced relationship with said web. In this way the motion of the envelop web and of the patch web may be more accurately synchronized and 15 the relation of the patches of the envelop more exactly determined, owing to the fact that an unperforated envelop web travels more truly than a perforated web which is apt to be unsteady because of the capacity 20 for stretching which is imparted to a web by perforating it with large window apertures.

By the operation of my machine after the window patch has been applied to the running envelop web, the latter is subsequently perforated with the customary window apertures, and then severed to form individual envelop blanks and folded so as to form a completed envelop. During the operation of 35 folding, the window patch which had been previously applied to the web, is brought into its ultimate and proper relationship to the window aperture and secured thereto.

A further improvement afforded by my 40 machine is the employment of a temporary adhesive for holding the patch in proper relation to the envelop web. A permanent adhesive is subsequently applied either to the patch or to the web in the region of the window. The folding of the envelop material brings the patch into proper relationship to the window aperture to which it is secured by the permanent adhesive at which time the temporary adhesive having served 45 its purpose, ceases to be effective.

The plan is, however, not essential to my machine since in the operation of the apparatus, as I have disclosed it in the drawings, the window patch may be permanently 50 secured to the unperforated envelop material in the position shown in the drawings, and

be subsequently folded back and permanently secured to the region of the window aperture.

Referring to the drawings, Figure I, is a 60 longitudinal elevation of my machine, certain of the parts being conventionally illustrated in order to more clearly indicate the successive operations which the machine performs.

Fig. II, is a side elevation on an enlarged scale of the patch applying and gumming mechanism.

Fig. III, illustrates the initial patch gumming rollers.

Fig. IV, is a longitudinal section of the patch gumming and applying mechanism.

Fig. V, represents the window aperture cutting dies.

Fig. VI, is a longitudinal section showing 75 the severing means and the envelop forming means.

Figs. VII, VIII, IX, and X, show respectively the second gumming rollers, the feed rollers follow the second gumming rollers, the severing knives, and the tail trimming knives.

Figs. XI, XII, XIV, and XV, are detail views to aid in understanding the operation of the envelop forming mechanism.

Fig. XIII, is a perspective view showing the operation of the creaser roll.

Fig. XVI, is a plan view of the envelop web showing successive stages of envelop formation.

Fig. XVII, illustrates an unfolded but otherwise completed envelop.

Fig. XVIII, is a sectional view of the folded envelop illustrating the points of adhesion of the window patch.

Referring to Fig. I, the roll of envelop material 1, is continuously fed between the feed rollers 2, 2, which, with the other rollers hereinafter referred to, are driven by the countershaft 3.

After passing between the feed rollers, 2, 2, the envelop web is advanced between the walls of a creasing device 4, by which its sides receive the longitudinal creases 5, (see Fig. XVI), which facilitate the ultimate 105 turning down of the side flaps. The crease 5, having been applied longitudinally near the edge of the web, but the entire web still running flat, it is passed between the edge cutting rollers 6, 6, by which portions of the 110 edges are cut away, leaving the edge flaps 7, 7, as shown in Fig. XVI.

The envelop web is next advanced through the patch gumming and applying mechanism, which is shown on an enlarged scale in Figs. II, and IV. By this mechanism, 5 patches cut from the intermittently progressing patch roll 8, are applied in proper relation to the running envelop web, and secured thereto by an adhesive, temporary or permanent, as may be desired, but not as yet 10 in their ultimate relationship to the envelop web.

The patch forming material 9, passing under and over guide rollers, as shown in Fig. I, is drawn upwardly, and after passing the 15 guide roller 10, see Fig. IV, runs between the rollers 11, and 12, the latter of which is provided at intervals around its periphery with gum applying or printing strips 13, the edges of which are kept properly supplied 20 with gum, by contact with the gumming roller 14, partially submerged in the gum receptacle 15. The intermittent motion of the patch web is occasioned by the intermittent rotation of the rollers 11, and 25 12, which is accomplished as follows:—The rollers are geared together and the roller 11, carries the ratchet 16, which is driven by a pawl 17, pivoted to a wrist plate 18, swung by a pawling lever 19, the end of which is 30 pivoted to the lever arm 20, rotating on the shaft 21, which is driven by appropriate gearing from the main shaft.

After passing between the rollers 11, and 35 12, and receiving transverse impressions of gum, from the roller 12, (which is more fully illustrated in Fig. III), the patch web is drawn beneath the tension guide roller 22, which rotates between arms 23, pivoted at 40 24, and held under the tension by the coiled springs 25. This guide roll 22, presses upon the patch web, only at the surface of projecting collars which coincide with the breaks in the gum impressions corresponding to the breaks of the printing strips shown 45 in Fig. III.

The patch web properly gummed and intermittently advanced as has been described, is severed to form individual patches, by the shearing knives 30, and 31, of which the former is fixed, while the latter is attached to a vertically reciprocating carrier 32. This carrier runs in suitable vertical slideways, and is reciprocated by means of a link 33, which connects it with the arm 34, set upon 55 a rock shaft 35, to which a rocking motion is imparted by the lever 36, the free end of which carries a roller 37, actuated by a cam 38, mounted on a shaft 39. By the vertical reciprocation of the carrier 32, each successive patch is severed from the patch roller, and carried upward by the knife blade 31, and applied to the lower side of the advancing envelop web. To assist in this application, a roller 40, bearing a pressure face 41, 60 65 rotates above the envelop web, in opposition

to the movable knife blade 31, supporting the envelop web against the pressure of said movable blade, which thus causes each patch, after it has been cut from the patch web, to adhere to the envelop web, by means of 75 the gum strip which has been applied to it. The roller 40, is driven by pinions from the shaft 39, as shown in Fig. II.

Thereafter, the envelop web carrying upon its under surface a succession of patches, 75 passes between feed rollers 42, and 43, (Fig. I) and then between rotating window cutting dies 44, and 45, more fully shown in Fig. V, whereby, the envelop web is perforated for the formation of the window 80 apertures.

The stage which has thus been reached, is illustrated in the central region of the plan of the envelop web disclosed by Fig. XVI.

Thereafter the envelop web passes between 85 the rollers 47, and 48, whereby gum is impressed upon the side of the patch which is ultimately to be folded against the region of the window apertures, and also upon the edge flaps. The positions of these gum applications are indicated toward the right hand of Fig. XVI, and the contour of the gumming roller 48, is indicated in Fig. VII.

From this point the envelop web, still 90 unsevered, is passed vertically between the feed rollers 50, 51, which are shown in detail in Fig. VIII, and which are so shaped as to avoid contact with gummed parts of the web; and thence between the shearing dies 52, and 53, shown in an enlarged scale 100 in Fig. IX, whereby the web is subdivided into separate envelop blanks, and thence to the tail trimmers 54, and 55, shown on an enlarged scale in Fig. X, whereby the tails or lower corners of the envelop blank are 105 cut away, leaving a completed blank as shown in Fig. XVII, in which figure the dotted lines indicate the removed tails.

From this point the envelop blanks pass 110 in succession into the control of the creaser and carrier roll 60. This contains transverse notches 61, 61, for forming the bottom fold of the envelop, and transverse notches 62, 62, for forming the flap fold of the envelop. Each of these notches contains a 115 yielding pressure edge 63. A rotary folder 64, carries a yielding straight edge 65. As the envelop blank passes between this and the creaser roll, it is folded and driven into the notch 61, along the line which is 120 to form the bottom of the envelop, which is there held by the pressure edge 63. Thus held the rotation of the creaser roll carries the envelop blank through the folder 66, and thence in proximity to the roll 70, which 125 carries a straight edge 71, which acts in conjunction with the flap creasing notch 62, to effect formation of the crease for the flap. The roll 70, also carries a gumming surface 72, rotating in contact with the gum 130

roll 73, by which the flap gum is imprinted upon the margin of the flap of the envelop.

By the co-action of the parts thus described, the envelop blank is completely 5 folded to form the front and back of the envelop, an operation the beginning of which is more clearly seen in Fig. XIII. As a result of this fold the window patch has likewise been folded so as to bring it 10 in its proper ultimate relationship to the window aperture. As the envelop passes between the creaser roll 60, and the roll 70, sufficient pressure is exerted to cause the window patch to adhere firmly around the 15 region of the window by means of the gum imprint which has already been applied. As a result the window patch will adhere to the interior of the envelop in a way clearly represented in Fig. XVIII, where 20 76, represents the line of adhesion, due to the original strip of gum imprinted upon the patch by the gumming roll 12, Fig. III, while 77, 77, represent lines of adhesion due to the gum imprinted by the gum roll 48. 25 The latter being in immediate proximity to the edges of the window, is necessarily a permanent adhesive, but the adhesion along the line 76, is sufficiently accomplished by the use of a temporary adhesive, such as a 30 very dilute rice paste.

It is obvious that by different adjustments, the original line of adhesion 76, between the window patch and the envelop web may be located elsewhere, and may require for 35 the proper use of the envelop that this original adhesion cease when the envelop is put into use. In this case, a temporary adhesive must be used.

During the creasing operation which has 40 been described as taking place as a result of the action of the creaser roll 60, there has simultaneously proceeded a folding over of the side flaps of the envelop. This is accomplished by the ears 80, and 81, on 45 said roll 60. Accordingly, the completed envelop, needing only the drying of the flap gum, is carried by the rotation of the creaser roll into position to be dropped upon the fingers 82. The cam surface 83, actuates 50 the straight edge within the notch 62, to take part in the formation of the flap crease, while the cam surface 84, actuates the straight edge in the notch 62, to effect the 55 release of the envelop when it is to be allowed to fall upon the fingers 82.

From this point the envelop passes between rolls 85, 86, and is from thence delivered to clips 87, of an endless carrier 88, by which the envelops are carried to permit 60 the drying of the gum upon the flap before they are discharged for packaging. The latter operations have been meagerly described, because they are already well-known in this art.

65 It will be understood that it is character-

istic of my device that the window patch is initially applied to the running envelop material at a point other than the region of the window opening, and ordinarily before any window opening is formed therein, with 70 the advantage of the more accurate positioning of the patch to the envelop web than is otherwise obtainable in continuously operating mechanism of this character. Subsequently the required permanent adhesive for 75 accomplishing the ultimate attachment of the window patch to the window opening is applied, and in connection with the folding of the envelop the window patch is brought into proper relation to the window 80 to accomplish its permanent adherence thereabout.

Having thus described my invention, I claim:

1. In a window envelop machine, the combination of means for applying window patches to running envelop material at successive intervals; means for subsequently cutting apertures in the envelop material; means for supplying adhesive for permanent attachment of the window patch in the region of the apertures; and means for folding the envelop material, whereby during the formation of the envelop the patch is brought into proper registration with the 95 aperture.

2. In a window envelop machine, the combination of means for applying window patches to running envelop material at successive intervals; means for subsequently 100 cutting apertures in the envelop material; means for severing the patched and apertured envelop material into envelop blanks; and means for folding said envelop blanks whereby during the process of envelop formation, the patch is brought into proper registration with the window aperture.

3. In a window envelop machine, the combination of means for applying patches at successive intervals to running envelop material; means for cutting apertures in the envelop material in a region removed from that upon which the patch was applied; means for supplying adhesive for permanent attachment of each patch; and means for 110 changing the position of the patch, whereby it is brought into proper registration with the aperture, and adherence around the edges thereof.

4. In a window envelop machine, the combination of means for continuously advancing envelop material; means for applying window patches to such envelop material at successive intervals; means for subsequently cutting apertures in the envelop material; 125 means for applying adhesive to the envelop material in the region of each window opening; means for thereafter severing the patched apertured and gummed material into envelop blanks; and means for folding 130

said envelop blanks, whereby during the formation of the envelop the patch is brought into proper registration with the window aperture.

5. 5. A device for supplying patches to and cutting apertures in an advancing envelop web, comprising means for applying a strip of adhesive near the rear edge of each patch; means for causing said patches to adhere by 10 that edge to the envelop web; and means for cutting apertures in said patched web, each one somewhat to the rear of the adhesive edge of each patch.

6. In a window envelop machine, the combination of a device for supplying patches to and cutting apertures in an advancing envelop web, whereby there is produced an apertured web with patches, one in advance of each aperture adhering to the web along 20 the edge nearest the aperture; means for supplying adhesive for permanent attachment of each patch in the region of each aperture; and means for subsequently folding back each patch into position to adhere 25 to the region of the window aperture and to cover the same.

7. In a window envelop machine, the combination of means for applying patches to running envelop material at successive intervals by means of a temporary adhesive; 30 means for cutting apertures in the envelop material; means for supplying permanent adhesive for attachment of the patch in the region of the aperture; and means whereby 35 the patch is transferred into proper regis-

tration with the aperture, and permanent adhesion thereabout.

8. In a window envelop machine, the combination of means for applying patches to a running envelop web and cutting apertures 40 therein, so that each aperture has a patch adhering to the web a short distance from each aperture by the edge nearest said aperture, the remainder of the patch being free; means for supplying adhesive in the region 45 surrounding the aperture; and means for folding the patch back along a line parallel to its original adherent edge, so as to cause the body of the patch to overlie the aperture and adhere to the surrounding region. 50

9. In a window envelop machine, the combination of means for applying a temporary adhesive to a patch web, subdividing the same into patches, and applying the patches to a running envelop web; means for cutting apertures in said envelop web and for applying permanent adhesive around the region of said apertures; and means for subdividing the envelop web into envelop blanks and folding the same into envelopes, whereby 55 during the process of envelop formation, the patch is transferred into position to permanently adhere to the region of the aperture.

In testimony whereof, I have hereunto signed my name at Philadelphia, Pennsylvania, this thirteenth day July, 1917.

GEORGE W. SWIFT, JR.
